UNITED STATES PATENT OFFICE.

JOHN J. MALONE, OF NEW HAVEN, CONNECTICUT.

DOOR-LATCH.

1,033,110.

Specification of Letters Patent. Patented July 23, 1912.

Application filed August 22, 1911. Serial No. 645,330.

To all whom it may concern:

Be it known that I, JOHN J. MALONE, a citizen of the United States, residing at New Haven, in the county of New Haven and State of Connecticut, have invented certain new and useful Improvements in Door-Latches, of which the following is a specification, reference being had therein to the accompanying drawings.

10 My invention relates to a new and improved door latch, referring more particularly to that type of latch used upon the door of an automobile or other motor vehicle.

15 It is the object of my invention, among other things, to construct such a latch so that it may be operated from the top or side of the door by turning the respective handles in either direction, as well as to so design 20 the same that it may be produced with few parts capable of being readily assembled and manufactured at the minimum cost.

25 To these, and other ends, my invention consists of the new and improved door latch 25 as herein set forth, and more particularly set forth in the claim.

Referring to the drawings in which like numerals designate like parts in the several figures; Figure 1 is an inside view of my 30 improved door latch; Fig. 2 is a side view thereof; Fig. 3 is an edge view thereof; Fig. 4 is a perspective view of the latch; and Fig. 5 is a perspective view of one of the followers.

35 In the practice of my invention, I provide a body member 1, having a face plate 2 at one end and a lug 3 thereon adjacent to the opposite end and near the elongated recess 4. Slidable between the lugs 5—5 upon the 40 body member 1, is the latch 6, the head 7 of which projects through an opening in the face plate 2. Movement of this latch away from the body member is prevented by the plate 8 that is secured at one end to the lugs 5—5 by the screws 9 and at the other end to the face plate 2 by the lips 10—10 that enter openings in the said face plate. A slot 11 is provided in the outer end of said plate to permit movement of the 50 latch head 7. Lateral movement of the tail of the latch is prevented by the lug 12 on the body member, that enters the slot 13 in said tail and having a washer 14 fixed thereon by the screw 15. A spiral spring 16 55 fixed at one end to a post 17 on the body member and with its free end against the

tail of the latch, exerts its pressure so as to hold the latch with its head projecting beyond the face plate 2, as shown in Figs. 1 and 2. From the side of the door the latch 60 is moved rearwardly by rotation of the spindle 18 through the handle 19, upon which is the follower 20, having the arms 21 thereon with rounded ends that engage the shoulders 22 upon the latch. This spindle is 65 supported in part by the plate 8, and an opening 23 is provided in the latch to permit said spindle to pass therethrough. From the top of the door the latch is moved rearwardly by rotation of the spindle 24 70 through the handle 25, said spindle being journaled within the lug 3 and having a follower 26 upon the inner end thereof, of substantially the same shape as the follower 20, the arms 27—27 thereon corresponding 75 with the said arms 21, and contacting with the front face 28 of the wing 29 that projects laterally from the tail of said latch. A pocket 30 in said wing receives that portion of the follower 26 that does not comprise 80 the arms 27, as shown in Figs. 2 and 3. Upon the underside of the wing 29 is a tongue 31 that projects into the recess 4, provided for clearance of the follower 26 during its rotation. 85

In operation the latch is secured to the door of an automobile or other motor vehicle, in a well known manner, and operated manually from either the top or side of the door by merely rotating the spindles 18 and 90 24 in either direction.

Knobs or similar devices may be substituted for the handles 19 and 25, if desired, and in other ways the details of my invention may be changed, so that I do not 95 limit myself to the exact construction herein shown and described, but claim all that falls fairly within the spirit and scope of my invention.

What I claim as new and desire to secure 100 by Letters Patent, is:—

In a device of the character described, the combination with a latch, having a head thereon, an opening therethrough in the rear of the head, a shoulder upon both sides of said opening, a wing upon one side of the end thereof opposite to said head, said wing having a pocket therein at substantially a right angle to the said opening, with contact faces upon either side thereof, that are 105 at substantially a right angle to the aforesaid shoulders; of a body member; two spin- 110

dles rotatably connected with said body member at substantially a right angle to each other, one of said spindles passing through the aforesaid opening; and a follower fixed to each of said spindles, each of said followers having arms, the contact faces of which are in substantially the same line, said line being upon one side of the center of said spindle and substantially parallel

with a line drawn through the center thereof at a right angle thereto.

In testimony whereof I affix my signature in presence of two witnesses.

JOHN J. MALONE.
